KEG DUMPING DEVICE

Leslie J. Hawkins, Colden, N. Y., assignor to
Honan-Crane Corporation, Lebanon, Ind., a
corporation of Indiana

Application August 3, 1950, Serial No. 177,529

4 Claims. (Cl. 222—166)

1

This invention relates to improvements in a keg dumping device, and more particularly to a device for unloading kegs containing nails, screws, bolts, nuts, pins, small parts machined or to be machined, or any other items that might be conveniently packed in a keg, the device being highly desirable for use in a manufacturing plant to facilitate the emptying of kegs and the retention of the contents in a convenient location for a worker, although the invention may have other uses and purposes as will be apparent to one skilled in the art.

In the past, considerable difficulty has been experienced in the emptying or dumping of kegs, especially in manufacturing plants where it is necessary to retain the contents of the keg easily available to a workman utilizing such contents. Heretofore, most of the dumping of the kegs was accomplished by hand, such procedure being dangerous to the workmen, there was risk of injury to the parts by way of spilling, and an objectionable amount of time usually wasted in endeavoring to place the dumped items in a handy location to the workmen. Obviously, if a keg were disposed adjacent the workman it was necessary not only to knock out the end of the keg, but to remove all the customary nails holding that end so as to eliminate injury to the workman.

With the foregoing in mind, it is an important object of the instant invention to provide a keg dumping device in which a full keg may be easily disposed, and a part of the device readily rotated to quickly dump the contents of the keg.

Another object of the invention is the provision of a keg dumping device, mobile in character, which is not only capable of readily dumping a keg, but which also may retain the parts dumped from the keg in a handy hopper easily accessible by a workman, the entire device being readily movable from one location to another as may be desired.

It is also a feature of this invention to provide a keg dumping device including a rotatably mounted keg holding structure equipped with a readily accessible hopper to receive the contents of a dumped keg, and wherein the keg holding structure is easily elevated to any desired or suitable height.

A further feature of the invention resides in the provision of a keg dumping device having a rotatable cage or cradle for the reception of a keg to be dumped, and a hopper to receive the contents of the keg, whereby it is not necessary to remove or knock out the nails holding a keg head, but merely necessary to punch out the head of the keg.

2

Still another object of this invention resides in the provision of a keg dumping device embodying a rotatable keg holding cradle having a bottom and an adjustable top which may be clamped over the open end of a keg, such top being provided with a suitable opening through which the contents of the keg may pass when the cradle and the keg therein are inverted.

Also an object of the invention resides in the provision of a keg dumping device embodying a lift support readily movable to a desired height, and a keg holding cradle pivotally carried by that support, the support having latching or locking means to maintain the cradle against accidental movement with either end of the cradle uppermost.

Still another feature of the instant invention resides in the provision of a simply constructed, economical, highly durable and readily usable keg dumping device, the device requiring only one man to operate it, and the device maintaining the contents of the keg readily available at a most convenient height and location to a workman.

While some of the more salient features, characteristics and advantages of the instant invention have been above pointed out, others will become apparent from the following disclosures, taken in conjunction with the accompanying drawings, in which—

30 Figure 1 is a pictorial illustration of a keg dumping device embodying principles of the instant invention, showing a keg therein, after the keg has been dumped;

35 Figure 2 is a fragmentary pictorial illustration of the structure of Fig. 1, taken from the opposite side thereof, and illustrating the apparatus in position to receive a keg to be dumped;

40 Figure 3 is an enlarged fragmentary vertical sectional view through the keg holding cradle and receiving hopper, taken substantially as indicated by the staggered section line III—III of Fig. 1, looking in the direction of the arrows; and

45 Figure 4 is an enlarged fragmentary vertical sectional view illustrating the mounting of the lift yoke and keg cradle, and taken substantially as indicated by the line IV—IV of Fig. 3.

As shown on the drawings:

In the illustrated embodiment of this invention there is shown an upright supporting structure in the form of a frame 1 preferably fabricated from angle iron. A subframe structure 2 is preferably provided on the side of the main frame to which a suitable winch 3 is secured as seen in Figs. 1 and 2. This winch may be manually operated by means of a handle 4 through a worm or other equivalent drive, and the subframe pro-

vides greater stability for the entire structure when a load is placed on the winch. Caster wheels 5 may be provided on the base of both the main and subframes in order to render the entire structure mobile, so that the complete device may be readily moved from place to place as desired.

At each side thereof the frame is provided with a pair of spaced vertically disposed rails 6-6, defining therebetween a track and at the same time functioning as an integral part of the frame. Inside the frame is a substantially U-shaped lift yoke 7, with the bight at the top and connected to the end of a cable 3 attached to the aforesaid winch, the cable passing over suitable pulleys 9 journaled in the top member of the frame. As seen best in Figs. 3 and 4, each side leg of the lift yoke 7 is provided with one or more flanged guide wheels or rollers 10, two vertically spaced rollers being illustrated. The flange portion of each such guide wheel overlies the inner edges of the track rails 6-6, while the barrel portion of each wheel extends between the track rails to ride against one or both of the confronting faces of the track rails. With this construction, it will be noted that the lift yoke may be readily elevated or lowered relatively to the frame by means of the winch, the guide wheels stabilizing the yoke and holding it steady during its up or down travel. Obviously, with the aid of the winch the yoke may be stopped at any desired height and retained at that level indefinitely.

The lift yoke carries a suitable keg holding cage or cradle 11, and in the illustrated instance this cradle 11 is of somewhat skeleton formation, being suitably fabricated from angle irons and flat bars. As seen clearly in Figs. 1 and 2, one side wall of the cradle is preferably left open so that a keg may readily be placed in and removed from the cradle. The cradle is also provided with a pair of opposed outwardly projecting trunnions 12, there being one mounted in each side of the cradle preferably centrally or near the center of gravity of the cradle. As seen clearly in Fig. 4, these trunnions are journaled in the respective side legs of the lift yoke 7 so that the entire cradle 11 is rotatable about the trunnions relatively to the lift yoke. As also seen clearly in Figs. 3 and 4, one or both of the trunnion carrying side members of the cradle is provided with a pair of apertures 13, one on each side of the trunnion. Each of these apertures is sized to receive the shank of a headed pin 14 inserted through an aperture in the adjacent side leg of the lift yoke 7, and thus the cradle may be locked or latched in fixed position with either end uppermost.

As seen clearly in Fig. 2, the cradle is preferably provided with a solid bottom 15 upon which a keg 16 may be initially seated when the device is in the position seen in Fig. 2.

A top 17 is adjustably connected to the other end of the cradle, and in the illustrated instance this top is maintained in position at the front or loading side of the cradle by means of a pair of elongated bolts 18-18, and at the rear side preferably with only a single similar bolt 19. This cover 17 is provided with a central aperture 20 through which the contents of the keg may be dumped into an outwardly and downwardly inclined and open topped hopper 21 carried by the cradle top 17. As seen clearly in Figs. 1 and 3, this hopper projects outwardly from the body of the device so as to be readily

accessible to a workman. Around the opening 20 the top 17 is provided with an inwardly extending flange 22 positioned to circumscribe the adjacent end margin or rim 23 of a keg, and maintain the keg steady during the unloading or dumping thereof.

In operation, the instant invention is extremely simple and highly satisfactory. Assuming that a new keg of material is needed, it is simply necessary to punch out the head of the keg, without regard to any protruding nails or other head holding means. The keg is then placed in the cradle 11 with the open end uppermost, and with the apparatus in the position seen in Fig. 2. When the keg is so positioned, the adjustable top 17 is clamped against the open end of the keg by means of the bolts 18 and 19, spacers 24 being utilized if desired or needed. It will be noted that the open end of the keg is circumscribed by the aforesaid flange 22 so that the keg is firmly held in position. The entire device may then be moved to any desired location if such is necessary, and when it is desired to dump the keg it is a simple means to elevate the lift yoke by means of the winch 3 so that the keg is disposed at any desired height. Then the pin 14 may be withdrawn, the cradle and keg inverted, and the pin reset in the other aperture 13 of the cradle. Upon inversion, the contents of the keg pass through the opening 20 in the cradle top or cover 17 and cascade into the hopper 21 which will now be in the position seen in Figs. 1 and 3. The keg contents are readily accessible in a most convenient manner to a workman who need only remove them in any desired quantity from the protruding portion of the hopper 21. Only one man is needed to operate the entire device, and there is no contingent danger to the operator or a possibility of loss by spillage of contents. Further, the structure is extremely simple in operation, highly efficient and time saving in use, and may be economically manufactured.

It will be understood that modifications and variations may be effected without departing from the scope of the novel concepts of the present invention.

I claim as my invention:

1. In a keg dumping device, a supporting structure, a lift support movable upwardly and downwardly in said structure, a keg holding cradle pivotally mounted in said lift support, latch means carried by said lift support to anchor said cradle in position with either end uppermost, a bottom in said cradle, an adjustable top in said cradle having a central opening therein, an inwardly extending flange around said opening to circumscribe the adjacent end margin of a keg in said cradle, and a downwardly and outwardly extending hopper carried by said cradle in communication with said opening to receive the contents of the keg upon inversion of the cradle, said hopper being open-topped and extending to one side of the supporting structure to hold the contents of the keg handy to a workman.

2. In a keg dumping device, a support, a keg holding cradle rotatably mounted in said support, latch means carried by said support to hold said cradle in fixed position relatively to said support with either end of the cradle uppermost, a bottom in said cradle, an adjustable cover in said cradle having an opening therein, and a laterally extending hopper on said cradle in communication with said opening to receive the contents of a keg upon inversion of the cradle.

3. In a keg dumping device, a support, a keg holding cradle rotatably mounted in said support, latch means to secure the cradle to the support with either end of the cradle uppermost, a bottom in said cradle, an adjustable cover in said cradle having an opening therein, an inwardly extending flange on said cover around said opening to circumscribe the end margin of a keg on said bottom, and a laterally projecting inclined hopper on said cradle in communication with said opening to receive the contents of a keg upon inversion of the cradle.

4. In a keg dumping device, an upright supporting frame, means defining opposed tracks in said frame, a lift yoke, guide wheels on said yoke to ride said tracks, a keg holding cradle, opposed trunnions on said cradle journaled in said lift yoke, latch means on said yoke to secure said cradle in position with either end uppermost, means to elevate and lower said lift yoke, a bot-

tom in said cradle, a cover having an opening therein, means to clamp said cover over a keg in said cradle, and a laterally extending open-topped hopper connected with said cover to receive the contents of the keg.

LESLIE J. HAWKINS.
